(57) **CLAIM**

The ornamental design for a plunger handle, as shown and described.

DESCRIPTION

FIG. 1 is a top perspective view of a plunger handle showing our new design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a top plan view thereof.

The end of the handle is shown broken away to indicate indeterminate length.
